(57) **CLAIM**

The ornamental design for a fluid delivery device, as shown in the drawings.

DESCRIPTION

FIG. 1 is an upper perspective view of a first embodiment of our new design for a fluid delivery device.

FIG. 2 is a lower perspective view thereof.

FIG. 3 is a back elevation view thereof.

FIG. 4 is a front elevation view thereof.

FIG. 5 is a left elevation view thereof.

FIG. 6 is a right elevation view thereof.

FIG. 7 is a top plan view thereof.

FIG. 8 is a bottom plan view thereof.

FIG. 9 is an upper perspective view of a second embodiment of our new design for a fluid delivery device.

FIG. 10 is a lower perspective view thereof.

FIG. 11 is a back elevation view thereof.

FIG. 12 is a front elevation view thereof.

FIG. 13 is a left elevation view thereof.

FIG. 14 is a right elevation view thereof.

FIG. 15 is a top plan view thereof; and,

FIG. 16 is a bottom plan view thereof.

The broken lines shown in the figures depict portions of the fluid delivery device that form no part of the claimed design. The shade lines shown represent surface shading and not surface ornamentation or material type.
